CLAIM

The ornamental design for a lane light, as shown and described.

DESCRIPTION

FIG. 1 is a perspective view of a lane light showing our new design;

FIG. 2 is a left side view thereof;

FIG. 3 is a front view thereof;

FIG. 4 is a back view thereof; and,

FIG. 5 is a top view thereof.

The broken lines are included for the purpose of illustrating portions of the lane light and form no part of the claimed design.

The symbolic break in the drawings indicates the boundary of the claimed design.
